SEWING MACHINE OR THE LIKE

Jiro Kosugi, Suginami-ku, Tokyo, Japan, assignor to Janome Sewing Machine Co. Ltd., Tokyo, Japan

Filed Feb. 28, 1962, Ser. No. 69,011

Claims priority, application Japan Aug. 31, 1961

Term of patent 14 years

(Cl. D70—1)

FIG. 1

FIG. 2

FIG. 3

FIG. 4

FIG. 5

FIG. 1 is a front elevational view of a sewing machine or the like, showing my new design;

FIG. 2 is a top plan view thereof;

FIG. 3 is a rear elevational view thereof;

FIG. 4 is a head-end elevational view thereof; and

FIG. 5 is a standard-end elevational view thereof.

The dominant features of my design reside in the portions shown in full lines.

I claim:

The ornamental design for a sewing machine or the like, as shown and described.
